Primary Examiner — Susan E Krakower*Assistant Examiner* — L. A. Grabenstetter(74) *Attorney, Agent, or Firm* — Lee & Hayes, PLLC(57) **CLAIM**

The ornamental design for an interactive camera device, as shown and described.

DESCRIPTION

FIG. 1 is a first perspective view of an interactive camera device, taken from the front;

FIG. 2 is a second perspective view of the interactive camera device, taken from the back;

FIG. 3 is a front view of the interactive camera device as shown in FIG. 1;

FIG. 4 is a back view of the interactive camera device as shown in FIG. 1;

FIG. 5 is a left-side view of the interactive camera device as shown in FIG. 1;

FIG. 6 is a right-side view of the interactive camera device as shown in FIG. 1;

FIG. 7 is a top view of the interactive camera device as shown in FIG. 1; and,

FIG. 8 is a bottom view of the interactive camera device as shown in FIG. 1.

The broken lines represent features of the interactive camera device which form no part of the claimed design.

1 Claim, 7 Drawing Sheets(56)
